EXCAVATING APPARATUS

John W. Page, Chicago, Ill.

Application April 7, 1934, Serial No. 719,549

3 Claims. (Cl. 214—138)

This invention relates to improvements in excavating apparatus and, more particularly, to that type embodying a boom and dipper stick, the latter carrying at its end a bucket, hoe, or 5 equivalent element for digging, scraping, cutting, excavating, or the like.

Among the features of my invention is the extension of the boom beyond the hinge of the dipper stick, with all portions of the boom line 10 that reach the end of the boom extended substantially to the end of the dipper stick, so that all of the lift on the boom is transmitted through the dipper stick. By this arrangement, the extension of the boom beyond the hinge point may 15 be relatively short and good control of the bucket is obtained with a reduced tendency to "jack-knife".

The bucket may be rigidly attached to the end of the dipper stick or hinged thereon.

20 Other features and advantages of my invention will appear more fully as I proceed with my specification.

In those forms of devices embodying the features of my invention shown in the accompanying drawings—

Figure 1 is a view in side elevation of a device with the bucket rigidly attached to the dipper stick; Fig. 2 is a diagrammatic view in front elevation showing the reeving of the boom line; 30 Fig. 3 is a view similar to Fig. 1, showing the bucket hinged to the end of the dipper stick; and Fig. 4 is a view similar to Fig. 2, showing the reeving of boom line of the device of Fig. 3.

As shown in the drawings, the apparatus includes a suitable platform 10, preferably mounted 35 on traction members 11, and carrying suitable machinery (not shown) adapted to operate the winches 12 and 13 for controlling the boom line 14 and the drag line or loading line 15, respectively.

The platform 10 carries a mast or upright 16 supported by bracing members 17, 17. Hinged to the platform at 18 is a boom 19. Near its end, the boom has hinged at 20 on its underside 40 one end of a dipper stick 21. 22 and 23 are stops to limit the outward swing of the dipper stick with respect to the boom. There are two sheaves 24, 24 at the top of the mast 16, and three sheaves 25, 25, 25 at the end of the boom 19.

50 As thus far described, the two devices shown are substantially the same.

I shall now describe further the device of Figs. 1 and 2 with the bucket rigidly attached to the end of the dipper stick. As here shown, the bucket is indicated by 26 and may be of a

more or less conventional shape, with a bottom, sides and back, the front or digging end being left open. The bucket is rigidly attached to the lower or free end of the dipper stick by the bolts or rivets 27, 27.

The boom line 14 is reeved over the sheaves 24 and 25 and over a sheave 28 fastened to the bucket 26. The outer end of the line 14 is attached to the bucket at 29. In this manner, all portions or strands or reaches of the boom line 14 that reach the end of the boom are extended substantially to the end of the dipper stick, so that all of the lift on the boom is transmitted through the dipper stick. As here shown, the attachment of the boom line to the 10 end of the dipper stick is effected by its attachment to the bucket, the latter being fastened to the end of the dipper stick. 15

The loading line 15 is fastened to the front of the bucket 26 by the bridle chains 30 and 20 preferably passes between the guide pulleys 31, 32 at the bottom of the mast and over the guide pulley 33 carried by the boom.

In operation, the movements of the bucket and boom are controlled by the lines 14 and 15. 25

In the device of Figs. 3 and 4, the bucket 126 resembles, in general, a Page bucket and is hinged to the free end of the dipper stick at 127. The boom line 14 is reeved over the sheaves 24 and 25 and over a sheave 128 attached to a 30 short lever 150 pivoted at 151 near the free end of the dipper stick 21. The outer end of the line 14 is attached at 129 to the cage carrying the sheave 128. The free end of the lever 150 is attached by a chain 152 to a pair of angle 35 irons 153 fastened on the top of the bucket. A plurality of holes 154 in these angle irons permit fastening of the chain at different points more or less removed from the pivot 127. Here, again, all portions or strands or reaches of the 40 boom line 14 that reach the end of the boom are extended substantially to the end of the dipper stick, so that all of the lift on the boom is transmitted through the dipper stick. Here, however, the attachment of the boom line to the 45 end of the dipper stick is accomplished through the lever 150 and through the chain 152 and bucket, the lever being attached to the stick at 151 and the bucket at 127. The attachment 50 of the line 14 to the bucket through the lever 150 and chain 152 causes tension on this line to tend to rock the bucket on its pivot 151.

The loading line 15 is fastened to the front of the bucket 126 by the bridle chains 130 and 55

preferably passes under a guide pulley at the bottom of the mast 16.

In operation, the movements of the bucket and boom are controlled by the lines 14 and 15 and the relative tensions on these two lines will control the rocking of the bucket on its pivot 127. Change of position of the attachment of the line 14 in the holes 154 will affect the tendency of said line to rock the bucket on its pivot 10 127 in respect to the lift of said line on the boom.

While I have shown and described certain embodiments of my invention, it is to be understood that it is capable of many modifications. 15 Changes, therefore, in the construction and arrangement may be made without departing from the spirit and scope of the invention as disclosed in the appended claims, in which it is my intention to claim all novelty inherent in 20 my invention as broadly as permissible, in view of the prior art.

What I regard as new, and desire to secure by Letters Patent, is:

1. Excavating apparatus of the character described, including: a boom; a dipper stick with one end hinged to the boom at a point removed from the end of the boom; a bucket hinged to the free end of the dipper stick; a loading line attached to the bucket; a lever hinged to the dipper stick near the bucket; a connection between said lever and the bucket; and a boom 10 line extending over the end of the boom with its outer end attached to said lever. 5

2. Apparatus as claimed in claim 1, in which the boom line is reeved over the end of the boom and in which all portions of the boom line 15 that reach the end of the boom are extended and attached to said lever.

3. Apparatus as claimed in claim 1, in which the connection between the lever and the bucket is adjustable. 20

JOHN W. PAGE.
